The ornamental design for a measuring cap, as shown and described.

DESCRIPTION

FIG. 1 is a front perspective view of a first exemplary embodiment of my design;

FIG. 2 is a front view thereof;

FIG. 3 is rear view thereof;

FIG. 4 is right side view thereof;

FIG. 5 is left side view thereof;

FIG. 6 is top view thereof;

FIG. 7 is bottom view thereof;

FIG. 8 is a front perspective view of a second exemplary embodiment of my design;
FIG. 9 is a front view thereof;
FIG. 10 is rear view thereof;
FIG. 11 is right side view thereof;
FIG. 12 is left side view thereof;
FIG. 13 is top view thereof; and,
FIG. 14 is bottom view thereof;
FIG. 15 is a front perspective view of a third exemplary embodiment of my design;
FIG. 16 is a front view thereof;
FIG. 17 is rear view thereof;
FIG. 18 is right side view thereof;
FIG. 19 is left side view thereof;

FIG. 20 is top view thereof;
FIG. 21 is bottom view thereof;
FIG. 22 is a front perspective view of a fourth exemplary embodiment of my design;
FIG. 23 is a front view thereof;
FIG. 24 is rear view thereof;
FIG. 25 is right side view thereof;
FIG. 26 is left side view thereof;
FIG. 27 is top view thereof; and,
FIG. 28 is bottom view thereof.

The broken lines shown in the drawings represent portions of the measuring cap which form no part of the claimed design.
